FRANK HARRIS STANFORD, OF ELIZABETH, NEW JERSEY, ASSIGNOR, BY MESNE ASSIGNMENTS, TO STANFORD METAL RAILROAD TIE COMPANY, OF ELIZABETH, NEW JERSEY, A CORPORATION OF NEW JERSEY.

RAIL TIE AND ANCHOR.

1,076,612.

Specification of Letters Patent.

Patented Oct. 21, 1913.

Application filed April 15, 1913. Serial No. 761,217.

To all whom it may concern:

Be it known that I, FRANK H. STANFORD, a citizen of the United States, and a resident of Elizabeth, in the county of Union and State of New Jersey, have invented a new and Improved Rail Tie and Anchor, of which the following is a full, clear, and exact description.

This invention relates to railway construction and has particular reference to means for supporting the usual railway rails.

Among the objects of the invention is to devise a metallic cross tie adapted for the support of a novel form of rail securing devices.

A further object of the invention is to produce a combined rail brace and anchor whereby the rail will be supported so as to resist all sliding and tilting movements by a simple and reliable construction.

A still further object of the invention is to improve this class of devices so as to enable the fastening means to be secured in place in the most expeditious manner.

Another object of the invention is to provide means for easily adjusting the rails lengthwise of the cross ties as is desirable at times because of the change in gage of the railway or other purposes.

The foregoing and other objects of the invention will hereinafter be more fully described and claimed and illustrated in the drawings forming a part of this specification in which like characters of reference indicate corresponding parts in all the views, and in which—

Figure 1 is a perspective view of the main portion of the cross tie made in accordance with this invention; Fig. 1^a is a longitudinal sectional view of the central portion of the same indicating the manner of insulating one end of the tie from the other and yet providing for a strong rigid joint including a downwardly projecting anchor; Fig. 2 is a vertical section substantially on the line 2—2 of Fig. 3; Fig. 3 is a plan view of one end of the cross tie showing adjacent ends of railway rails; Fig. 4 is a transverse section of the cross tie on the line 4—4 of Fig. 3; and Figs. 5 and 6 are perspective views of the several parts of the clamping mechanism.

Referring more particularly to the drawings, I show a metallic cross tie 10 comprising substantially duplicate end portions 11 made preferably of rolled sheet metal of substantially uniform thickness throughout. Said end portions each comprise a flat body 12 adapted to receive and support a rail R. A pair of flanges 13 extend angularly from the edges of the body 12, the angle formed between said flanges and body being slightly more than 90°, shown in Fig. 4. The body 12 is also provided with a plurality of slots 14 and 15 extending downwardly therethrough in pairs. At the inner end of each end portion is substantially a flat bar 16, and the ends 16 of both portions are connected substantially centrally of the cross tie by means such as indicated in Fig. 1^a. The connecting means shown comprises a flat plate 17 spanning the joint. An angle member 18 comprising a horizontal arm 19 and a downwardly projecting arm 20 is secured rigidly to the end of the plate 16, as by rivets 21. The arms 20 of the two adjacent members extend downwardly and cooperate with the ballast to prevent tendency of the tie to shift lengthwise of itself or lateral movement of the track. Said members 20 are connected by bolts 22 and the plate 17 is connected to the other parts of the structure by a series of bolts 23. When it is desired to insulate one end of the cross tie from the other, as is usual in electrified railways, I insert strips of fiber or other insulation 24 between contiguous flat surfaces and spools 25 of the same adjacent the several spools, as shown in Fig. 1^a.

The anchorage means for the rails securing them to the cross tie comprises a pair of clamps 26 and 26' co-operating with each of the members 11. Each of these clamps includes a plate 27 adapted to lie substantially snugly on the upper surface of the body 12 adjacent the base flange 28 of the rail. The brace 29 extends inwardly and upwardly from the plate 27 of the clamp 26 and cooperates at its upper edge 30 with the rail just beneath the head 31 thereof and adjacent the upper portion of the web 32, as shown in Fig. 2. A pair of lips 33 extend inwardly from the plate 27 on each side of the brace 29 and over the rail base flange 28.

and serve to clamp the said base flange to the plate 12. A pair of toes 34 extend downwardly from the side edges of the plate 27 through the slots 14 and are provided 5 with a pair of points 35 which extend beneath and snugly embrace the portion 36 of the cross tie plate, and hence prevent upward displacement of the base flange of the rail. Said toes 34 are preferably rounded 10 at their ends opposite the points 35, as shown at 37, to facilitate the introduction thereof into place with the toes through the slots. Said rounded portions 37 may coöperate in any suitable manner with the outer ends of 15 the slots 14, but where I provide for longitudinal adjustment of the clamps with respect to the cross tie there is provided a slight space, as indicated at 38 in Fig. 2, for such purpose.

20 The clamp 26 may be locked in place by any suitable means such, for instance, as a strong bolt 39 extending transversely through the flanges 13 of the cross tie and through a pair of holes 40 in the toes 34.

25 As above intimated, I prefer to provide pairs of holes 41 through the flanges 13 for the accommodation of the bolt 39 in either of two locking positions. As shown in Fig. 2, the clamp 26 is locked inwardly with respect to the outer end of the cross tie, providing for a narrow gage adjustment of the rail R, but when the rail is to be adjusted outwardly, the rounded shoulder 37 of each 30 of the toes 34 will abut snugly against the end of the slot 14. Since the latter described position of the clamp 26 may represent the adaptation of the device for a single adjustment, I prefer to construct the curvature 35 37 with a center located substantially close to the point of contact of the end 30 of the brace with the rail so that the toes may be passed freely downwardly through the slots. Since, however, the devices are adapted for adjustment as above described, the bolt 39 40 may be depended upon to constitute the sole locking means for the clamp, and by providing the space 38 the toes 34 may be dropped freely through the slots and the clamp then given a longitudinally sliding movement, 45 bringing the lips 33 and points 35 into engaging position. When the clamps 26 and 26' are intended for use adjacent rail joints as shown in Fig. 3, I prefer to form the brace 29 with lugs 29' which pass directly 50 through bolt holes 42 formed in the rail ends as usual, as shown in Fig. 2. By this means the rail ends are locked in the desired juxtaposition.

The clamp 26' has a pair of toes 43 which 60 project downwardly through the slots 15, and this clamp serves to cooperate with the other edge of the base flange 28 in a manner similar to the clamp 26. This clamp, therefore, has a lip 44 coöoperating with the upper

surface of said flange, and a pair of points 65 45 coöperating with the under surface of the portion 36 of the plate 12. I prefer also to provide points 45 on the opposite ends of the toes for interlocking coöperation with the structure at the opposite ends of the 70 slots 15 in one position of adjustment, as shown in Fig. 2. The clamp 26' is locked in place by a bolt 39' which corresponds to the bolt above described with respect to the flanges and several alined holes 40' and 41'. 75

By the means herein described, I provide rigid clamping means for the rail, outward tilting of the rail being prevented by the lip 44 of one clamp and the brace 29 of the other. Outward slidable movement of the 80 rail is prevented by the clamps, especially the clamp 26 held in place by its bolt 39.

Having thus described my invention, I claim as new and desire to secure by Letters Patent:—

85

1. The herein described clamp for rail-ways, the same comprising a plate having a pair of slots extending vertically therethrough, a clamp having a pair of toes pro-jecting downwardly through said slots, 90 lip extending from each of the toes over the base flange of the rail, said toes each having a point extending beneath said plate, the clamp also including a brace extending up-wardly at an angle into coöperation with 95 the rail web and head, and a bolt extending transversely through said toes securing the clamp in position with respect to said plate.

2. The combination with the usual form of railway rail having a base flange, a ver-tical web and head, of a metallic tie having a pair of slots extending therethrough ad-jacent one edge of the base flange, means ex-tending upwardly from the tie coöperating with the opposite edge of the base flange, a 100 unitary rail brace and anchor having spaced toes extending downwardly through said slots and embracing spaced portions of the tie beneath the rail base flange, and also including a pair of lips in vertical aline-ment with said toes coöperating with the upper surface of the base flange and a brace 105 between said lips coöperating with the up-per portion of the rail, and means detach-ably securing said brace and anchor to the 110 upper surface of the tie.

3. The herein described rail tie and an-chor, the same comprising a substantially flat plate having pairs of slots extending downwardly therethrough adjacent a rail 120 to be supported thereon and also having a pair of angularly disposed flanges having pairs of alined transverse holes extending therethrough beneath the plate, a pair of clamps each including a plate adapted to 125 lie against the upper surface of the afore-said plate, a pair of toes extending down-wardly through a pair of said slots, a pair

of lips adapted to extend over the rail flange, and a pair of points extending from said toes beneath said plate, and a bolt extending transversely through certain of said flange holes and through said toes to secure said clamps and rail in either of several positions with respect to the tie.

In testimony whereof I have signed my name to this specification in the presence of two subscribing witnesses.

FRANK HARRIS STANFORD.
